UNITED STATES PATENT OFFICE.

EDWIN E. BARNEY, OF NEW ROCHELLE, NEW YORK, ASSIGNOR TO REMINGTON TYPE-WRITER COMPANY, OF ILION, NEW YORK, A CORPORATION OF NEW YORK.

TYPEWRITING MACHINE.

Application filed June 2, 1926. Serial No. 113,241.

My invention relates to typewriting and like machines and more particularly to tabulator mechanism. More specifically stated, the invention relates to devices for selectively setting and for clearing or restoring 5 the column stops.

The main object of my invention is to provide simple and inexpensive, yet highly efficient, devices of the character specified 10 which may be readily incorporated in existing typewriting machines, and may be combined with existing tabulator mechanism, without modifying, or materially modifying, the structural features of such existing 15 structures.

To the above and other ends which will hereinafter appear, my invention consists in the features of construction, arrangements of parts, and combinations of devices set 20 forth in the following specification and particularly pointed out in the following claims.

In the accompanying drawings, wherein like reference characters designate corresponding parts in the different views,

25 Figure 1 is a fragmentary rear elevation with parts in section of part of a typewriting machine equipped with the devices of my invention.

Figure 2 is a detail fragmentary top plan 30 view of the same.

Figure 3 is a detail side elevation of the stop setting device represented in its actuated position and showing a column stop set thereby.

35 Figure 4 is a detail rear elevation of the stop clearing device and some of the column stops; the view showing the stop clearing device in its actuated position.

Figure 5 is a detail view taken transversely through the column stop bar and showing a column stop in its normal ineffective position on the bar.

Figure 6 is a fragmentary, enlarged detail 40 front elevation of the column stop bar.

45 Figure 7 is a fragmentary, detail fore and aft, vertical sectional view of the parts represented in Fig. 1; the section being taken on the line 7—7 of Fig. 1 and looking in the direction of the arrows at said line.

50 My invention is shown, in the present instance, embodied in a No. 12 Remington machine in which the invention may be readily incorporated without modifying, or materially modifying, the structural features of

the machine as they now exist; only a sufficient number of parts of said machine being shown to illustrate the invention in its embodiment therein. It should be understood, however, that the invention is not restricted to embodiment in the machine referred to 55 but may be applied to typewriting and like machines generally.

The carriage 1 may be of the usual construction and includes a rear cross bar or rail 2 grooved to receive crossed bearing rollers 3, which also are received in an oppositely disposed groove in a fixed guide rail 4 secured to the top plate 5 of the machine. The carriage with corresponding supporting means at the front thereof is thus supported and guided to travel from side to side of the machine over the top plate under control of its escapement and tabulator mechanism.

The escapement mechanism may be of the 75 usual construction represented in part by a feed rack 6 and a feed pinion 7 with which the rack meshes to control the step-by-step letter-feed movement of the carriage under the power applied thereto by the usual 80 spring drum, not shown. The feed rack 6 is supported on arms 8 pivoted at 9 on the rear cross bar 2 of the carriage to enable the rack 6 to be lifted out of mesh with the pinion 7, and thus free the carriage from control of 85 its escapement mechanism.

Rearwardly extending bracket arms 10 fixed to the carriage, support a column stop bar 11 fixed to said arms. This stop bar has on opposite sides thereof interdental spaces 90 12 at letter space intervals throughout the effective length thereof, and in each of which spaces between the teeth 12^a is received a bifurcated sheet metal column stop 13. In accordance with my invention the teeth 12^a 95 on the column stop bar are preferably arranged on the front and rear sides of the bar so that the interdental spaces 12 permit a vertical movement of each of the column stops from the uppermost ineffective position to a lowermost effective position where it may coact with a key controlled counter stop, as will presently appear.

In order that each column stop may be retained against accidental displacement 100 from either of said positions, and in order to prevent each of said column stops from dropping off or being accidentally removed

from the bar, I provide means which will be hereinafter specifically described. It will suffice at the present to understand that each column stop 13 is retained against accidental displacement from either the effective or ineffective position to which it may be set.

Each of the lowermost effective column stops coacts with a suitable counter or co-operative key controlled tabulator stop. In the present instance such counter stop and the means for actuating it are the same as are disclosed and claimed in the application of George A. Seib Serial No. 29,874 filed May 13, 1925 and will now be briefly described. Mounted on the top plate of the machine is a sheet metal bracket plate 14 on the inner end of which is mounted a member, slide or stop 15 to receive a limited vertical sliding movement on the bracket. This member has a stop at its upper end that comprises two oppositely disposed bevel faces 16 and 17 and an intervening slot 18 in which a projected column stop is received to arrest the carriage. The counter stop, arranged directly beneath the column stop bar, is elevated to effective position by an arm or lever 19 pivoted at 20 on the bracket plate 14. The outer end portion 21 of this arm is adjustably secured to the main body of the arm 19, and is pivoted at 22 to a depending link 23 actuated by a suitable key at the keyboard. The inner end portion of the arm 19 carries a leaf spring 24, the inner free end of which underlies a pin 25 connected to the slide 15. When the lever 19 is rocked from normal position it elevates the counter stop 15 through the spring 24 and interposes said stop in the path of the projected column stop. This same movement of the lever 19 effects a lifting of the feed rack 6 to free it from the pinion 7, and enable the carriage to travel until arrested by the first active column stop coacting with the counter stop. The lifting of the feed rack 6 is effected by a shoe 26, (Fig. 1) carried by and off-set laterally on the lever 19 and extending beneath the teeth of the rack.

The tabulator mechanism having been described, I will now proceed to describe the stop setting and clearing devices of the present invention.

A comparatively heavy bracket 27, preferably of cast metal, is secured by screws 28 to the top plate in the rear of the stop bar 11 and near the fore and aft median plane of the machine, which is indicated by the axis of the feed pinion 7 in Fig. 1. Pivoted on a headed and shouldered pivot screw 29, threaded into the inner free end of the bracket, is a sheet metal stop setting member 30. This member is preferably in the nature of an angular lever, one arm 31 of which is substantially horizontally disposed and projects forward from its pivot and overlies the column stop bar and the stops carried thereby.

The thickness of the blade-like stop setting arm 31 corresponds substantially to the thickness of each of the column stops 13, so as to coact individually and with said stops and move them selectively to effective position, depending on the position of the carriage in its line of travel. The other arm 32 of the stop setting member is substantially vertically disposed and swings fore and aft of the machine to produce respectively an up and down movement of the arm 31. The lower end of the arm 32 is bifurcated at 33 to receive a flat lug 34, integral with and off-set laterally from the upper end of an upright crank arm 35 which has an integral hub 36 at its lower end secured by a pin 37 to a rock shaft 38. The construction is such that when the parts are in the actuated position, represented in Fig. 3, the opposite jaws 39 and 40 at the bifurcated end of the arm 32 will bind or crank against the interposed lug 34 and act to arrest further motion of the parts away from normal position. In other words, at this time there can be no further angular movement of the arms 32 and 35 in the direction of the arrows in Fig. 3; consequently said arms and all other parts connected thereto are arrested. At this time the column stop is arrested in its projected position and this in itself may be relied on to arrest the stop setting member and the parts connected therewith. The movement of the parts in the opposite direction is limited by the arm 32 coacting with a stop pin 41 extending from the bracket 27. The rock shaft 38 extends in the direction of the travel of the carriage and is located in the rear of the column stop bar. The inner end of the rock shaft 38 is reduced at 42 where it is received in a bearing opening in the foot piece of the bracket 27. The outer reduced end portion of the shaft 38 is received in a bearing opening in a bracket 43, secured by screws 44 to the top plate. The shaft 38 at its outer end extends beyond the bracket and has secured thereto, by a pin 45, the hub of a depending crank arm or actuating member 46 which terminates in a finger piece 47. It will be seen that this finger piece while at the rear of the machine is located near one side thereof where it may be conveniently manipulated by the operator. A coiled spring 48 surrounds the shaft 38 and is secured at one end to the bracket 43 and at the opposite end to a collar 49 secured to the shaft 38 by a screw 50. The power of this spring is exerted to turn the shaft 38 in an anti-clockwise direction, as the parts appear in Fig. 7, and to return it and the parts connected therewith to normal position, represented in this figure. The force of spring 48 may be increased or decreased by loosening the screw 50 and turning the collar 49 on the shaft 38 in one direction or

the other and tightening the screw to hold the collar in its newly adjusted position on the shaft. A forward movement of the finger piece 47 is effective to move the stop setting arm 31 down from the Fig. 7 to the Fig. 3 position, forcing the registering column stop 13 down on the column stop bar to effective position, as shown in the last mentioned figure. When the finger piece 47 is released the spring 48 will return the stop setting devices to normal position, ready to move the next column stop selected for use down into effective position. Such selected stop is determined by the position of the carriage in its line of travel, it being understood that there is preferably provided one column stop for each letter-space position of the carriage.

My improved means for clearing restoring or returning the column stops to ineffective position will now be described.

The bracket 27 is provided with a forwardly extending projection 51 tapped fore and aft of the machine to receive the threaded end of a shouldered pivot screw 52 having an enlarged head 53. The stop restoring or returning device, shown in the present instance, is made of sheet metal and comprises two parallel members or cam supporting lever arms 54 united at the lower edges thereof by an integral cross piece 55. The arms 54 are further united by a shouldered rivet 56 that projects at its rear end beyond the arms to provide an actuating or connecting pin 57, for purposes which will presently appear. The arms 54 extend in the direction of the travel of the carriage, and near the right hand ends thereof are provided with registering openings that receive the unthreaded shank of the screw 52 and pivot thereon. It will be seen that these arms are prevented from moving axially on the pivot screw 52 in one direction by the head 53 of the screw, and in the opposite direction by the projection 51 on the bracket. The upper edge of each of the arms 54 is shaped to provide oppositely disposed cammed faces or wipers 58 and 59. These cams coact with the lower edges of the projected column stops to cam them successively up to ineffective position when the arms 54 are elevated to the Fig. 4 position and the carriage is moved in the line of its travel. Whether the cams 58 or 59 are effective for this purpose depends on whether the carriage is moved from left to right or from right to left in returning the stops.

It will be seen that the pivoted lever arms 54 and the cams thereon are directly beneath the column stop bar and the stops carried thereby, and that the pivotal movement of the arms from ineffective to effective position is in the same general direction as the movement of the stops on the bar to ineffective position. In short, both

have an upward movement at this time. It follows therefore that if there should be any stops 13 in the path of the cams 58 and 59 when the latter are elevated, such stops will merely be moved up to ineffective position by the cams and not obstruct the movement of the cams to effective position.

I have provided a very simple and inexpensive, yet highly effective, means for controlling the restoring or clearing cams which will now be described.

The rearwardly extending, connecting pin 57 on the arms 54, hereinbefore referred to, is received in a cam slot 60 of a sheet metal cam member or lever 61, pivoted at 62 to the bracket 27. The member 61 is extended up beyond its pivot to provide an arm 63 which terminates in an off-set finger piece 64. A coiled contractile spring 65 is secured at one end to a pin 66 projecting rearwardly from the member 61, the opposite end of said spring being anchored on a screw 67 threaded into extension 51 of the bracket 27. This spring 65 returns the member 61 and the arms 54 to the normal ineffective position when the operator releases the finger piece 64, in which position the parts are arrested by the pin 57 coacting with the head of a screw 68 carried by the escapement bracket 69. The movement of the parts in the opposite direction is arrested by the stops 13, when they are moved upward to the limit of their movement on the stop bar 11. Since the stops 13 can move no further in this direction there can be no further upward movement of the arms 54, nor a further operating movement of the cam member 61.

It will be seen that the levers 61 and 54 extend at substantially right angles one to the other, and that the cam slot 60 is eccentric to the pivotal center 62 on which the lever 61 turns, the pivotal movement of the member 61 being transverse to the pivotal movement of the arms 54. By reason of the construction and arrangement of the parts described, the pin 57 is substantially dead centered against the pivot 62 at all times under action of column stops on the restoring cams, such dead centering resisting the tendency to displace the restoring cams from effective position during the restoration of the column stops. Otherwise expressed, the stops 13 acting on the restoring cams 58, 59 cause the latter to exert a dead center thrust against the pivot 62 of the controlling lever 61, and thus resist any tendency to displace said cams from effective position. This will be appreciated from a consideration of Fig. 4 from which it will be seen that the reaction of the column stops against the restoring cams 58 or 59 tends to force the pin 57 down, but that this is effectively resisted by the dead center thrust of the pin 57 against the pivot 62.

62, and the restoring cams cannot be accidentally displaced, and there is no reaction against the finger of the operator in holding the restoring cams in effective position.

5 I will now describe the means for preventing an accidental displacement of the column stops on the stop bar, and for preventing an accidental detachment of the stops from the bar.

10 Referring more particularly to Figs. 3, 5 and 6, it will be seen that a spring 70 is secured at 71 to each column stop 13. This spring is provided with two arms 72 and 73 that extend upward, the former in the 15 rear and the latter in front of the stop bar 11. The upper end of the spring arm 72 is provided with a projection 74 which overlies an adjacent tooth 12^a of the stop bar. Said projection has a horizontally disposed 20 lower contact face 75 that coacts with the upper corner or edge of said adjacent tooth, as shown in Fig. 3, thus limiting the motion of the column stop to effective position, and preventing the stop from dropping off 25 or being accidentally detached from the bar. However, a removal of the stop may be effected, when desired, by springing the arm 72 and carrying the projection 74 to a position 30 where it will clear the coacting tooth 12^a of the bar.

The spring arm 73 on the opposite side of the bar carries a laterally extending projection 76 beveled at its top and bottom edges. Extending longitudinally of the 35 stop bar 11 is a groove 77 formed in the front face thereof, and providing a locking notch in the front edge of each forward tooth 12^a. The location of each of these notches is such that the projection or spring 40 detent 76 is seated therein when the associated stop 13 is in the effective position. This prevents the stop from being accidentally jarred or pushed up from effective position, as for example, when the stop 13 45 coacts with a bevel face 16 or 17 of the counter stop 15. The detent 76 does not, however, prevent the associated stop 13 from being positively cammed up to ineffective position by the restoring cam 58—59. 50 From an inspection of Fig. 5 it will be seen that when a stop 13 is thus cammed up to ineffective position, the projection 76 will spring over the upper edge of an adjacent tooth 12^a of the stop bar, thus holding the 55 stop from accidentally dropping from such position to the lowermost effective position. The force of this spring detent is insufficient, however, to materially affect or resist the setting of the stop by the stop setting devices.

60 From the foregoing it will be seen that I have provided simple and inexpensive means for attaining the results specified, and such means in practice have proved highly efficient.

Various changes may be made without departing from my invention as it is defined in the accompanying claims, and certain of the features thereof may be employed without others.

70 What I claim as new and desire to secure by Letters Patent, is:—

1. In a typewriting machine, the combination of a carriage, a series of column stops carried thereby and movable vertically thereon from ineffective to effective position and vice versa, and stop setting mechanism carried by the frame of the machine and co-operative selectively with said column stops depending on the position of the carriage in 75 its line of travel to move them to effective position, said stop setting mechanism comprising a rock shaft, a crank arm on said rock shaft, and a pivoted angular lever one arm of which constitutes a stop setting blade 80 that extends above said column stops and the other arm of which is operatively connected with said crank arm and by which the lever is rocked, said operative connection being formed by a bifurcation in one arm that receives the other arm, said connection limiting the motion of the stop setting mechanism in one direction.

85 2. In a typewriting machine, the combination of a carriage, a series of column stops carried thereby and movable vertically thereon from ineffective to effective position and vice versa, and stop setting mechanism carried by the frame of the machine and co-operative selectively with said column stops depending on the position of the carriage in 90 its line of travel to move them to effective position, said stop setting mechanism comprising a rock shaft that extends longitudinally in the direction of the travel 95 of the carriage and has an upstanding crank arm at its inner end and a depending finger piece at its outer end, a bracket detachably secured to the top plate of the frame of the machine, and an angular lever pivoted on 100 said bracket and having a substantially horizontally disposed arm that extends over the column stops and a substantially vertically disposed arm operatively connected to said 105 upright crank arm on the rock shaft.

110 3. In a typewriting machine, the combination of a carriage, a series of column stops carried thereby and movable vertically thereon from ineffective to effective position and vice versa, and stop setting mechanism carried by the frame of the machine and co-operative selectively with said column stops depending on the position of the carriage in 115 its line of travel to move them to effective position, said stop setting mechanism comprising a rock shaft that extends longitudinally in the direction of the travel of the carriage and has an upstanding crank arm at its inner end and a depending finger piece 120 at its outer end, a bracket detachably secured to the top plate of the frame of the machine, and an angular lever pivoted on said bracket and having a substantially horizontally disposed arm that extends over the column stops and a substantially vertically disposed arm operatively connected to said 125 upright crank arm on the rock shaft.

- cured to the top plate of the frame of the machine, an angular lever pivoted on said bracket and having a substantially horizontally disposed arm that extends over the column stops and a substantially vertically disposed arm operatively connected to said upright crank arm on the rock shaft, said operative connection being formed by a bifurcation in one arm that receives the other 10 arm, said connection limiting the operating movement of the stop setting mechanism, and a stop on said bracket with which said angular lever coacts to limit the return movement of the parts.
5. In a typewriting machine, the combination of a carriage, a column stop bar carried thereby, column stops mounted for vertical movement on said column stop bar to and from effective position, a key controlled co-operative stop movable up from beneath the 20 column stop to effective position, and stop setting mechanism carried by the frame of the machine and co-operative selectively with the column stops depending on the position of the carriage in its line of travel to move them to effective position, said stop setting mechanism comprising two brackets detachably secured to the top plate of the machine, a rock shaft extending longitudinally 30 in the direction of the travel of the carriage and mounted to turn in bearings in said brackets, a crank arm that extends upward from the inner end portion of said rock shaft in the rear of said column stop bar, a finger 35 piece depending from the other or outer end of said rock shaft, and an angular lever pivoted on one of said brackets and having one arm that extends substantially horizontally over said column stops and a second substantially vertically disposed arm that is operatively connected to the crank arm on said rock shaft, said operative connection being formed by a bifurcation in one arm that receives the other arm, 40 said connection limiting the operating movement of said stop setting mechanism.
6. In a typewriting machine, the combination of a carriage, a series of column stops carried thereby and movable thereon into and out of effective position, and stop returning mechanism carried by the frame of the machine and co-operative with said stops to return them to ineffective position, said returning mechanism comprising a restoring cam which co-acts with the effective stops to cam them to ineffective position, a hand actuated lever for controlling said cam, and connections between said cam and lever that enable the restoring cam to 50 substantially dead center against the pivot of said lever throughout the action of the latter and thus resist the displacement of the cam under the action of the stops thereon.
7. In a typewriting machine, the combination of a carriage, a series of column stops carried thereby and movable thereon into and out of effective position, and stop returning mechanism carried by the frame of the machine and co-operative with said stops to return them to ineffective position, said returning mechanism comprising a restoring cam which coacts with the effective 60 stops to cam them to ineffective position, a lever arm on which said cam is supported, a hand actuated controlling lever for said cam, and intermediate actuating connections between said last mentioned lever and said lever arm that enable the cam carrying lever 70 substantially to dead center against the pivot of said controlling lever and thus resist the displacement of said restoring cam under the action of the stops thereon.
8. In a typewriting machine, the combination of a carriage, a series of column stops carried thereby and movable thereon into and out of effective position, and stop returning mechanism carried by the frame of the machine and co-operative with said stops to return them to ineffective position, said returning mechanism comprising a restoring cam which coacts with the effective 80 stops to cam them to ineffective position, a hand actuated lever for controlling said cam, and a cam on said lever by which said restoring cam is actuated and through which the restoring cam substantially dead centers against the pivot of the controlling lever and thus resists the displacement of 90

6 the restoring cam under the action of the stops thereon.

9. In a typewriting machine, the combination of a carriage, a series of column stops carried thereby and movable thereon into and out of effective position, and stop returning mechanism carried by the frame of the machine and co-operative with said stops to return them to ineffective position, 10 said returning mechanism comprising a restoring cam which coacts with the effective stops to cam them to ineffective position, a hand actuated lever for controlling said cam, said lever having a cam slot therein, 15 and a pin connected with said restoring cam and received in said cam slot to actuate the restoring cam, the restoring cam exerting substantially a dead center thrust against the pivot of said controlling lever and thus 20 resist the displacement of the restoring cam under the action of the stops thereon.

10. In a typewriting machine, the combination of a carriage, a series of column stops carried thereby and movable thereon into 25 and out of effective position, and stop returning mechanism carried by the frame of the machine and co-operative with said stops to return them to ineffective position, said returning mechanism comprising a restoring cam which coacts with the effective stops to 30 cam them to ineffective position, a supporting lever on which said restoring cam is mounted, and a hand actuated controlling lever coacting with an arm of said supporting lever through an intermediate cam, the motions of the coacting arms of said levers being transverse one of the other so that the supporting lever will substantially dead center against the pivot of the controlling lever and thus resist the displacement of the restoring cam under the action of the stops 40 thereon.

11. In a typewriting machine, the combination of a carriage, a series of column stops 45 carried thereby and vertically movable thereon into and out of effective position, and stop returning mechanism carried by the frame of the machine and co-operative with said stops to return them to ineffective position, said returning mechanism comprising a restoring cam arranged beneath said stops and which coacts with the effective stops to cam them upward to ineffective position, a supporting lever for said cam, a hand actuated controlling lever having a cam slot 55 therein, and a pin on said supporting lever received in said cam slot, the arms of said levers having said cam slot and pin extending one transversely of the other so that the supporting lever will substantially dead center against the pivot of the controlling lever and thus resist the displacement of the re- 60

storing cam under the action of the stops thereon.

12. In a typewriting machine, the combination of a carriage, a column stop bar carried thereby, column stops vertically movable thereon into and out of effective position, a stop setting device carried by the frame of the machine and operable by a pivotal movement on the stops from above to move them selectively down to effective position, the stop to be selected depending on the position of the carriage in its line of travel, a bracket secured to the top plate of the machine and on which said stop setting device is pivoted, a key controlled counter stop beneath said column stops and movable upward to coact with the effective column stops, a restoring cam beneath said column stops and movable up to effective position to coact with the effective column stops, a lever on which said restoring cam is mounted, a hand actuated lever for controlling said restoring cam and which is pivoted on said bracket and extends transversely of said supporting lever, and means for operatively connecting said levers so that the pivot of the controlling lever will resist a downward movement of the supporting lever and thus resist a displacement of the restoring cam under the action of the stops thereon. 65 70 75 80 85 90 95

13. In a typewriting machine, the combination of a column stop bar having a longitudinally extending locking groove therein, stops shiftable vertically on said bar into and out of effective positions, means for preventing the accidental detachment of each of said stops from said bar and for holding each of said stops against accidental vertical displacement from its lowermost effective position and also from its lowermost ineffective position, said means including a spring carried by each stop and having an engaging projection that engages an upper corner of the bar when the associated stop is in the uppermost ineffective position and engages in said locking groove when the stop is in the lowermost effective position, a second projection on said spring which coacts with an upper corner of the stop bar to limit the motion of the stop in its movement to the lowermost effective position, means for moving said stops to the uppermost effective position, and means for moving said stops to lowermost ineffective position. 100 105 110 115

Signed at the borough of Manhattan, city of New York in the county of New York and State of New York this 1st day of June, A. D. 1926. 120 125

EDWIN E. BARNEY.
